COMBINED SHOE BRUSH, SCRAPER AND CLIP FOR SPORTSMEN

Donald R. Davis, 10864 E. Estates Drive, Cupertino, Calif., and Richard E. Jones, 24220 Hillview Drive, Los Altos Hills, Calif.

Filed July 18, 1960, Ser. No. 61,381

Term of patent 7 years

(Cl. D9—2)

FIG. 1 is a perspective view of a combined shoe brush, scraper and clip for sportsmen showing our new design therefor;

FIG. 2 is a top plan view thereof;

FIG. 3 is a bottom plan view thereof;

FIG. 4 is a front elevational view thereof;

FIG. 5 is a side elevational view thereof as seen from the right of FIG. 4, and

FIG. 6 is a rear elevational view thereof.

We claim:

The ornamental design for a combined shoe brush, scraper and clip for sportsmen, as shown.
